(57) **CLAIM**

The ornamental design for an electrical contact, as shown and described.

DESCRIPTION

FIG. 1 is a top, front, right side perspective view of an electrical contact, showing my new design;

FIG. 2 is a top, rear, right side perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof, a left side elevation view being a mirror image thereof; and,

FIG. 8 is an enlarged cross-sectional right side elevation view thereof, taken along section line 8-8 of FIG. 3.

The equal length broken lines in the drawings depict portions of the electrical contact that form no part of the claimed design. The dash-dot-dash lines define the boundaries of the claimed design.
